HUNTING KNIFE

John B. F. Champlin and Theodore H. Banton,
Little Valley, N. Y., assignors to Cattaraugus
Cutlery Company, Little Valley, N. Y., a corpora-
tion of New York

Application June 15, 1943, Serial No. 490,906

5 Claims.

(Cl. 279—95)

This invention relates to an improved hunting knife and more particularly to a novel handle therefor.

Heretofore, hunting knives in large majority have been provided with laminated handles primarily because of the difficulty experienced in solidly securing a one-piece hand grip on the tang of the blade.

It is therefore an object of the present invention to provide a hunting knife wherein the hand grip may be moulded, as of plastic or other suitable material capable of being fashioned in a single piece, and wherein the hand grip will be solidly and securely locked on the tang of the blade.

A further object of the invention is to provide a hunting knife having a handle embodying an anchoring plate internally of the hand grip for securing the hand grip in fixed position on the tang so that the grip will be prevented from shifting either forwardly or rearwardly.

Still another object of the invention is to provide a knife wherein the anchoring plate for the hand grip will be locked in place by a key coacting with the tang to bind said plate in position.

Another object of the invention, in this connection, is to provide a knife wherein any rearward end thrust on the hand grip of the handle will be communicated to the anchoring plate and through the key to the tang so that any rearward pull on the hand grip, when the knife is in use, will be sustained by the tang itself.

A further object of the invention is to provide a knife wherein the key will be so shaped that it may be inserted in the handle to lock the anchoring plate in place, but wherein the key will be also fashioned to coact with the tang for limiting the key against expulsion.

And the invention seeks, as a still further object, to provide a knife wherein the free ends of the portions of the tang engaging the key will be covered by a butt plate secured to the anchoring plate for the hand grip.

Other and incidental objects of the invention will appear as the description thereof proceeds, and in the drawing.

Figure 1 is a view of our improved knife showing the blade in side elevation and the handle in vertical section.

Figure 2 is a view showing the blade in top plan and the handle in horizontal section.

Figure 3 is a section on the line 3—3 of Figure 1.

Figure 4 is a fragmentary perspective view par-

ticularly showing the tang, anchoring plate, key and butt plate in proper relative position but disassembled.

In carrying the invention into effect, we employ a blade 10 from which extends a tang 11, preferably rectangular in cross section. For the major portion of its length, the tang is medially slotted from the rear end thereof, at a right angle to its width, to provide prongs 12 free at their outer ends, and these prongs are resilient. At the forward ends of the prongs lies a stop shoulder 13 therebetween.

Near their outer end portions, the prongs 12 are cut away at their inner confronting edges to provide a wedge-shaped socket 14 terminating in more or less vertical shoulders 15 on the prongs at the outer end of the socket or, in other words, the wide end thereof.

Slipped over the tang 11 to abut the heel of the blade 10 is a guard plate 16, and also slipped over the tang to abut said plate is a hand grip 17 of a length to terminate flush with the tang. Axially, the grip 17 is cored out to provide a slot 18 which snugly fits the tang at its forward end portion while at the rear end portion of said slot, from the zone of the shoulder 13 rearwardly, the slot is widened vertically to provide clearance spaces 19 gradually increasing in depth toward the free ends of the prongs 12. The hand grip is preferably unitary and may be of plastic or other suitable material capable of being pre-fashioned. Also, as will be understood, the hand grip may be of any chosen external contour.

Formed in the hand grip 17 at a right angle to the slot 18 is, as best seen in Figure 2 of the drawing, a medial, rectangular intersecting recess 20 provided at its forward end portion with converging shoulders 21. As will be observed, these shoulders extend from the zone of the shoulder 13 of the tang 11 to merge at their forward ends into the vertical walls of the slot 18.

Shaped to snugly fit the recess 20 of the hand grip 17 is a flat, resilient, rectangular anchoring plate 22 which is inserted between the prongs 12 of the tang 11 and is snugly received therebetween. As best seen in Figure 4 of the drawing, this plate is V-shaped at its forward end and formed in the forward end portion of the plate is a medial slot 23 defining like wedge-shaped terminals 24 which snugly straddle the tang 11 forwardly of the shoulder 13 thereof. As will be noted, the terminals 24 of the plate 22 are provided with outer, rearwardly diverging shoulders 25 which fit the converging shoulders 21 of the recess 20 of the hand grip 17 to coact with the

latter shoulders while the slot 23 terminates in a shoulder 26 to abut the shoulder 13 of the tang 11, the shoulder 26 lying substantially in a plane with the rear ends of the shoulders 25.

Formed in the plate 22 at its rear end portion is a medial slot 27 somewhat longer than the slot 23 of said plate and defining like parallel tines 28. When the plate is in position, these tines, as best seen in Figure 2 of the drawing, project slightly beyond the rear ends of the prongs 12 of the tang 11.

Formed to fit in the socket 14 between the prongs 12 of the tang 11 is a key 29 having a wedge-shaped head 30 from which extends a medial, rectangular stem 31 snugly received between the free ends of the prongs to terminate flush therewith. At the base of the stem are provided more or less vertical shoulders 32.

After the hand grip 17 and anchoring plate 22 have been assembled upon the tang 11, the key 29 is then inserted in the slot 27 of the plate 22, which slot is of a length to receive the key, and forced between the free ends of the prongs 12 until the head 30 of the key drops into the socket 14, when the shoulders 32 of the head 30 will engage behind the shoulders 15 of said prongs for locking the parts in place. The foregoing operation of the installation of the key explains the reason for the clearance spaces 19 in the slot 18 of the hand grip. As will be perceived, as the head 30 of the key rides between the free ends of the prongs, the prongs will be forced apart against the resilient action thereof and, therefore, the spaces 19 are of a depth to accommodate the spreading movement of the prongs as the key is inserted. If so desired, the spaces 19 may be later blocked by suitable wedges, not shown, or say appropriate cement or other like approved filler. The detail is entirely optional.

Attention is now directed to the fact that after the key 29 is installed, the forward end of the head 30 thereof will coat with the end wall of the slot 27 of the plate 22 for forcing the plate forwardly. Consequently, the shoulders 25 of the terminals 24 of the plate will be forced to coat with the shoulders 21 of the recess 20 of the hand grip 17 for forcing the hand grip forwardly into tight and permanent engagement with the guard plate 16. Either forward or rearward shifting of the hand grip on the tang 11 will thus be prevented. If so desired, the shoulders 15 of the prongs 12 of the tang may be inclined as may also the shoulders 32 of the head of the key 29 so that said shoulders will coat with each other to exert, as will be well understood, a forward wedging action on the key under the influence of the spring action of the prongs tending to assume a normal parallel position. The incline of said shoulders need be so slight that any attempt further than as seen in the drawing to show the inclination would result only in exaggeration. However, as will be perceived, a constant forward urge on the key will result to constantly bind the parts in place and take up any latent looseness therebetween.

Shaped to conform to the contour of the rear end of the handle is a butt plate 33 provided with apertures 34 to snugly receive the free ends of the tines 28 of the plate 22. As seen in Figure 2 of the drawing, the tines are of a length to project only partially through the apertures so that recesses are thus defined between the outer ends of the tines and the outer face of the plate, and filling said recesses are bonding clots 35 of

electric welding metal permanently securing the plate in position. As will be noted, the butt plate 33 is secured to the anchoring plate 22 rather than to the ends of the prongs 12 of the tang 11 because, first, to allow a clamping action of the prongs on the key 29 and, second, because the prongs, being a part of the blade 10, are of high carbon steel.

Having thus described our invention, what we claim as new is:

1. A knife including a blade having a tang provided with spaced prongs free at their outer ends, a hand grip disposed over the tang and provided internally with a recess terminating at its forward end in forwardly converging shoulders, an anchoring plate fitting in said recess and provided at its forward end with rearwardly diverging shoulders coacting with said first mentioned shoulders for limiting the grip against rearward movement, and a key disposed between the free ends of said prongs to engage therewith and with said plate for locking the parts in position.

2. A hunting knife including a blade having a tang provided with a shoulder and spaced longitudinally extending prongs, a hand grip fitted over the tang and engaging said shoulder, an anchoring plate within the grip and between said prongs, said plate forming an abutment engaged with a complementary surface on the grip and limiting the grip against rearward displacement on the tang independently of said plate, and means fixed between the rear ends of the prongs and abutting an end surface of the plate to form a stop locking the plate and grip against rearward displacement on the tang.

3. A hunting knife including a blade having a tang provided with a shoulder and spaced longitudinally extending prongs, a hand grip fitted over the tang and engaging said shoulder, an anchoring plate within the grip and between said prongs, said plate forming an abutment engaged with a complementary surface on the grip and limiting the grip against rearward displacement on the tang independently of said plate, means fixed between the rear ends of the prongs and abutting an end surface of the plate to form a stop locking the plate and grip against rearward displacement on the tang, and complementary means carried by the prongs and said first mentioned means slidably coacting in response to the resilient action of the prongs to urge said plate forwardly and maintain the grip in engagement with said shoulder.

4. A hunting knife including a blade having a tang provided with a shoulder and spaced longitudinally extending prongs provided at their inner edges with stop shoulders, a hand grip fitted over the tang and engaging said first mentioned shoulder, an anchoring plate within the grip and between said prongs, said plate forming an abutment engaged with a complementary surface on the grip and limiting the grip against rearward displacement on the tang independently of said plate, and a key disposed between said prongs and having shoulders thereon engaged by the shoulders of the prongs, said key abutting an end surface of said plate to form a stop locking the plate and grip against rearward displacement on the tang.

5. A hunting knife including a blade having a tang provided with a shoulder and spaced longitudinally extending prongs provided at their inner edges with oppositely disposed shoulders disposed near the rear ends of said prongs, a

hand grip fitted over the tang and engaging said first mentioned shoulder, an anchoring plate within the grip and between said prongs and provided at its rear end with spaced tines, said plate forming an abutment engaged with a complementary surface on the grip and limiting the grip against rearward displacement on the tang independently of said plate, and a key disposed

5 between said tines and maintained thereby between said prongs, said key having shoulders thereon engaged by the shoulders of the prongs and abutting an end surface of the plate between the tines to form a stop locking the plate and grip against rearward displacement on the tang.
